US0D1109079S

(12) **United States Design Patent** (10) **Patent No.:** **US D1,109,079 S**
(45) **Date of Patent:** **** Jan. 13, 2026**

(54) **CHARGER**

(71) Applicant: **MAKITA CORPORATION**, Anjo (JP)

(72) Inventors: **Kohei Hosokawa**, Anjo (JP); **Junya Yamaguchi**, Anjo (JP)

(73) Assignee: **MAKITA CORPORATION**, Anjo (JP)

(**) Term: **15 Years**

(21) Appl. No.: **29/947,680**

(22) Filed: **Jun. 17, 2024**

(30) **Foreign Application Priority Data**

Dec. 27, 2023 (JP) ..... 2023-027171 D

(57) **CLAIM**

The ornamental design for a charger as shown and described.

DESCRIPTION

FIG. 1 is a front, left, and top perspective view of a charger in accordance with our new design;

FIG. 2 is a rear, right, and bottom perspective view of the charger in accordance with our new design;

FIG. 3 is a front elevational view of the charger in accordance with our new design;

FIG. 4 is a rear elevational view of the charger in accordance with our new design;

FIG. 5 is a top plan view of the charger in accordance with our new design;

FIG. 6 is a bottom plan view of the charger in accordance with our new design;

FIG. 7 is a right side elevational view of the charger in accordance with our new design; and,

FIG. 8 is a left side elevational view of the charger in accordance with our new design.

The broken lines in the drawings illustrate portions of the charger which form no part of the claimed design.

1 Claim, 8 Drawing Sheets
